UNITED STATES PATENT OFFICE.

WILLIAM H. MINER, OF CHICAGO, ILLINOIS, ASSIGNOR TO W. H. MINER COMPANY, OF CHICAGO, ILLINOIS, A CORPORATION OF ILLINOIS.

DRAFT APPLIANCE FOR RAILWAY-CARS.

SPECIFICATION forming part of Letters Patent No. 775,278, dated November 15, 1904.

Application filed August 27, 1904. Serial No. 222,603. (No model.)

To all whom it may concern:

Be it known that I, WILLIAM H. MINER, a citizen of the United States, residing in Chicago, in the county of Cook and State of Illinois, have invented a new and useful Improvement in Draft Appliances for Railway-Cars, of which the following is a specification.

My invention relates to improvements in draft appliances for railroad-cars.

10 Heretofore in the railway draft appliances commonly in use the coupler has usually been constructed with a long integral draw bar or shank, to the rear end of which is rigidly secured by rivets a draw-bar extension, strap, 15 or yoke, which surrounds or incloses the draft-springs and followers which reciprocate between and are supported and guided by the upper and lower flanges or guides of the side plates or stop-castings, which are secured to the 20 car-frame. In this construction the springs and followers of the draft-rigging are necessarily arranged at quite a considerable distance from the front end or sill of the car, and the rigid draw-bar and draw-bar extension of 25 the coupler are necessarily of great length, especially in draft-rigging of the tandem type employing two or more springs arranged in tandem or longitudinally, one behind another, and often the space between the front transom or body-bolster and the end of the car is 30 scarcely long enough to properly accommodate the draft-rigging, and difficulty is also experienced, owing to the great length of the draft appliances, especially of the tandem type, 35 in so combining the coupler and its draft-rigging with the frame of the car as to enable the coupler to have the necessary lateral or horizontally -swinging movement to permit the cars coupled together in a train to pass 40 around curves without subjecting the couplers to severe lateral or binding strains, tending to disengage the couplers or to break the coupler or draft-rigging or wrench or disengage the same from the car.

45 The object of my invention is to provide a draft appliance of a strong, simple, and durable construction, by which all these objections or difficulties may be practically overcome and which will materially reduce the

cost or expense of the draft appliance as a 50 whole, as well as its length, and the room or space necessary to accommodate it on the car-frame and by which the springs and followers of the draft-rigging may be brought near to the front end of the car or directly adjacent 55 to the front sill of the car-frame, thus materially increasing the compactness and strength and efficiency of the draft appliance as a whole.

My invention consists in the means I employ to practically accomplish this object or 60 result—that is to say, it consists, in connection with the car-frame or the center sills or draft timbers or sills thereof, of a pair of side plates or stop-castings secured thereto, having the customary stops or shoulders for the 65 followers to abut against and provided at their front ends each with a rounded guide or bearing extending to the front end of the car and engaging a rearwardly-extending pivot ear or lug on the draw-head of the coupler to guide 70 the draw-head in its longitudinal movement and to permit the draw-head to swing laterally or horizontally on the vertical pivot, which pivotally connects its short pivot-lug or ear with the front end of the draw-strap or 75 yoke. By this means the draw-bar or long shank of the coupler - head is entirely dispensed with, thus materially diminishing the weight and cost of the coupler, and the draw-springs, followers, and side plates or stop- 80 castings of the draft-rigging are all brought near the front end of the car, thus making the draft appliance as a whole very compact and greatly increasing its strength and efficiency, while at the same time affording ample room or space between the front sill and the transom or body-bolster of the car-frame for the draft appliance and for its proper construction with any number of tandem-arranged springs that may be desired. 85

90 My invention also consists in the novel construction of parts and devices and in the novel combinations of parts and devices herein shown or described.

In the accompanying drawings, forming a 95 part of this specification, Figure 1 is a side elevation, partly in section, of a draft appliance embodying my invention. Fig. 2 is

a vertical cross-section on line 2 2 of Fig. 1. Fig. 3 is a plan view, partly in horizontal section, showing some of the parts broken away; and Fig. 4 is a cross-section on line 4 4 of 5 Fig. 1.

In the drawings, A A are the center sills or draft-sills of a car, to which the side plates or stop-castings B B are secured. A' is the front sill, and A² the carry-iron.

10 C is the coupler, the same being of the ordinary Master Car-Builders' type and having the customary draw-head C', pivoted knuckle C², knuckle pivot-pin C³, and lock C⁴. D is the strap or yoke, E E' tandem -arranged 15 springs, and F F' F² F³ the followers.

The side plates or stop-castings B have front stops or shoulders b for the front follower to abut against, and middle stops or shoulders b' b² for the two middle followers 20 to abut against, and a rear stop or shoulder b³ for the rear follower to abut against, and are each furnished at its front end with a curved or rounded guide or bearing b⁴ to engage the pivot lug or ear C⁵ of the draw-head 25 C', and thus guide the draw-head in its longitudinal movement and also limit the lateral or horizontally swinging movement of the draw-head on the vertical pivot, by which it is connected to the front end of the draw-strap or 30 yoke D. The curved or rounded guides or bearings b⁴ on the side plates or stop-castings B extend to the front ends of the side plates or stop-castings and to the front end of the car.

35 The draw-head C' of the coupler instead of having the customary long shank or draw-bar is provided simply with a short pivot ear or lug C⁵ and pivot-holes C⁶ in its upper and lower webs C⁷ C⁸ to receive the vertical pivot-pin D', by which the strap or yoke D is pivotally connected at its front end to the draw-head.

The draw-bar strap or yoke D bears at its looped or rear end d against the rear follower 45 and is provided with an abutment-block d' at its middle portion to bear against the two middle followers and with a filler-loop d² at its front end to bear against the front follower F. The strap or yoke D is furnished at its 50 pivot end with offsets or shoulders d³ to adapt its front or pivot end to enter between the upper and lower webs C⁶ C⁷ of the draw-head, and the filler-loop d² is provided with similar offsets or shoulders d⁴ to cause the same to 55 snugly fit between the upper and lower limbs of the strap or yoke D, to which said filler-loop is secured by the vertical pivot-pin D', by which the strap or yoke is pivotally connected to the draw-head. The pivot lug or 60 ear C⁵ of the draw-head fits between the upper and lower limbs of the filler-loop d² and is provided with a rounded or curved rear end d⁵, which abuts directly against the filler-loop, and thus communicates buffing strains on the 65 draw-head directly to the front follower and

relieves the pivot-pin D' of a portion of the strain, while also permitting the coupler-head to swing or turn laterally or horizontally on its vertical pivot, and for the same purpose the upper and lower limbs of the draw-strap 70 or yoke D are also preferably furnished with curved or rounded ends d³.

The draw-strap or yoke D extends through or in front of the carry-iron A² and is pivotally connected to the draw-head in front of 75 the carry-iron and the front or cross sill of the car, and this enables the draw-head to swing laterally or horizontally on its upright pivot freely within the limits prescribed by the curved guides or bearings b⁴ at the front 80 ends of the side plates or stop-castings B and also enables the draw-head, which is the part of the coupler liable to be broken and to require replacement, to be removed and replaced without taking down the draft-rigging 85 or removing the lower guide straps or plates b⁵ of the side plates or stop-castings B.

I claim—

1. In a draft-rigging for railway-cars, the combination with the center or draft sills of a 90 car, of a pair of side plates or stop-castings secured thereto, having stops or shoulders for the followers to abut against, and provided at their front ends with rounded guides or bearings on their inner faces extending to the 95 front end of the car, of a draw-strap or yoke, tandem springs and followers, and a coupler draw-head having a short pivot ear or lug pivotally connected to the front end of the draw-strap or yoke, substantially as specified. 100

2. The combination of center or draft sills of a car, tandem springs and followers, with side plates or stop-castings furnished with stops for the followers, and with rounded guides or bearings on their inner faces at 105 their front ends, of a draw-strap or yoke, and a coupler-head having a short pivot ear or lug pivotally connected to the front end of the draw-strap or yoke, substantially as specified. 110

3. The combination of center or draft sills of a car, tandem springs and followers, with side plates or stop-castings furnished with stops for the followers, and with rounded guides or bearings on their inner faces at 115 their front ends, of a draw-strap or yoke, a coupler-head having a short pivot ear or lug pivotally connected to the front end of the draw-strap or yoke, and a filler-loop at the front end of the draw-strap or yoke and embracing said pivot-lug, substantially as speci- 120 fied.

4. The combination of center or draft sills of a car, tandem springs and followers, with side plates or stop-castings furnished with stops for the followers, and with rounded 125 guides or bearings on their inner faces at their front ends, of a draw-strap or yoke, a coupler-head having a short pivot ear or lug pivotally connected to the front end of the draw-strap or yoke, and a filler-loop at the 130

front end of the draw-strap or yoke and embracing said pivot-lug, said pivot-lug having a curved rear end, substantially as specified.

5. The combination with a car-frame, of side plates or stop-castings secured thereto and extending to the end of the car, and provided with guides or bearings on their inner faces at their front ends, of a spring and followers, a draw-strap or yoke having its front end projecting beyond the end of the car, and a coupler draw-head pivotally connected to the front end of said draw-strap or yoke, substantially as specified.

6. The combination with a car-frame, of side plates or stop-castings secured thereto and extending to the end of the car, and provided with guides or bearings on their inner faces at their front ends, of a spring and followers, a draw-strap or yoke having its front end projecting beyond the end of the car, and a coupler draw-head pivotally connected to the front end of said draw-strap or yoke, said draw-head having a short pivot or lug at its rear, substantially as specified.

25 7. The combination with a car-frame, of side plates or stop-castings secured thereto and extending to the end of the car, and provided with guides or bearings on their inner faces at their front ends, of a spring and followers, a draw-strap or yoke having its front end pro-

jecting beyond the end of the car, a coupler draw-head pivotally connected to the front end of said draw-strap or yoke, said draw-head having a short pivot-lug at its rear, and a filler-loop at the front end of the draw-strap and embracing said pivot-lug, substantially as specified. 35

8. The combination with a car-frame, of side plates or stop-castings secured thereto extending to the front end of the car, and provided with rounded guides or bearings on their inner faces at their front ends, of a spring and followers, a draw-strap or yoke, and a coupler draw-head having a pivot-lug to which the front end of the draw-strap is pivotally connected, substantially as specified. 40

9. The combination with a car-frame, of side plates or stop-castings secured thereto extending to the front end of the car, and provided with rounded guides or bearings on their inner faces at their front ends, of a spring and followers, a draw-strap or yoke, and a coupler draw-head having a pivot-lug to which the front end of the draw-strap is pivotally connected, said pivot-lug having a rounded rear 50 end, substantially as specified. 55
